UNITED STATES PATENT OFFICE.

GEORGE T. PEARSONS, OF NEW YORK, N. Y.

FIRE-EXTINGUISHER.

1,378,609.

Specification of Letters Patent. Patented May 17, 1921.

Application filed November 27, 1916. Serial No. 133,521.

To all whom it may concern:

Be it known that I, GEORGE T. PEARSONS, a citizen of the United States, and a resident of the borough of Manhattan, in the 5 city, county, and State of New York, have invented certain new and useful Improvements in Fire-Extinguishers, of which the following is a specification.

This invention relates to fire extinguishers of the type in which a fire extinguishing liquid contained in a reservoir is discharged therefrom by a gas pressure generated in the reservoir by the reaction of the admixing of gas generating materials normally 10 maintained in a separated condition in a generator in the reservoir; and it is the primary object of the invention to improve the general construction of fire extinguishers of this type to cheapen the cost of construction and increase the efficiency thereof.

A further object of the invention is to provide an extinguisher of this type in which the gas generator is started, or the gas generating materials mix, by inverting the 25 extinguisher.

It is a further object of the invention to provide an improved generator adapted to be removably mounted in the reservoir whereby the generator may be removed from 30 the reservoir for the purpose of re-charging, cleaning or the substitution of another generator.

It is another object of the invention to provide an improved gas generator in which 35 provision is made to carry means through which the generated gas passes before it is expelled into the reservoir to render the gas dry and non-acid.

A further object of the invention is to 40 provide improved discharging means to at all times connect the discharge outlet with the liquid in the lowermost part of the reservoir in all positions of the extinguisher.

Other objects and advantages will here- 45 inafter appear.

In the drawings accompanying and forming a part of this specification Figure 1 is 50 a sectional side elevation of a fire extinguisher with an embodiment of my invention applied thereto; and Fig. 2 is a similar view showing the extinguisher in inverted position.

In the embodiment of my invention illustrated in the drawing there is provided a 55 reservoir for a fire extinguishing liquid, such as carbon tetrachlorid, said reservoir prefer-

ably comprising a body portion 3 closed at the bottom, as at 4, and constructed to form a standard for the extinguisher, and the upper end being open and adapted to be 60 closed by a removable cover 5. The cover has an opening centrally thereof to constitute the discharge outlet of the reservoir with a spring influenced, inwardly closing and outwardly opening, check valve 6 there- 65 in, said outlet having an extension 7 to the side of the reservoir with a manually operable valve 8 for a purpose to be hereinafter described.

The fire extinguishing liquid is expelled 70 from the reservoir by a suitable agent or gas, such as carbonic acid gas, generated by means within the reservoir. For this purpose I provide a gas generator comprising a receptacle 9 open at one end and having 75 an outlet in the closed end with a tube 10 secured in the outlet extending into the receptacle, the bore of the tube constituting a continuation of the outlet and having lateral ports 11. A second receptacle 12 having 80 one end open, which is in the nature of a cover, is adapted to have telescoping connection over the open end of the receptacle 9 and the open end coöperating with a flange 13 at the bottom of the receptacle 9 to provide 85 an entirely closed receptacle. Engaging in the first receptacle is a third receptacle 14 having an open end of less diameter than the receptacle 9 to provide a space between the walls of said receptacles, said third 90 receptacle being supported upon the outlet tube 10 and thereby providing a space between the bottoms of the two receptacles. This receptacle is adapted to contain one of the gas generating materials, such as bicar- 95 bonate of soda, and carries another receptacle 15 in the form of a glass bottle having another gas generating material, such as sulfuric or hydrochloric acid, free from the other gas generating material in the normal position of the extinguisher. The bottle 100 15 is closed by a stopper 16 having an outlet tube or tubes 17 and a projection 18 to engage with the end of the receptacle 12 to maintain the bottle within the third receptacle and the latter in position against the outlet tube 10.

The fire extinguishing liquid is of such a nature that it will not injure articles, such as wearing apparel, furniture, carpets or 110 the like with which it might come in contact, while the nature of the gas generating

materials is such as to destroy and ruin any such articles with which it may come in contact, and it often happens that part of the latter materials are carried off with the 5 generated gas into the reservoir and expelled with the fire extinguishing liquid with the above deleterious results. To prevent this contingency, means are provided to render the generated gas anhydrous or 10 dry and non-acid, by filtering the generated gas. For this purpose there is provided a material through which the generated gas passes to absorb any moisture in such gas, sodium carbonate having been found to 15 answer this purpose. This absorbing material is located in the space between the bottoms of the receptacles 9 and 12.

As stated, in this type of extinguisher the generator is started by inverting the extinguisher, and by inverting the extinguisher 20 the acid will flow from the receptacle 15 onto the soda, the reaction or gas passing up around the receptacle 14 and through the filtering material through the lateral ports 25 in the tube 10 into the reservoir.

The generator is carried in the reservoir in a tubular carrier 27, shown as a tubular member secured centrally to the bottom of the reservoir for a purpose to be herein- 30 after described, and the generator being an integral unit, it may be removed for the purpose of recharging, cleaning or the substitution of another generator. The receptacles 9, 12 and 14, as well as the outlet tube 35 10 of the generator, are preferably lead-coated to prevent corrosion by the fire extinguishing liquid or the gas generating materials.

A tube 28 is secured in the discharge outlet of the cover, the bore of said tube constituting a continuation of the discharge outlet. One end of the tube is closed and the tube extends into the reservoir to engage with the top of the generator when 45 the cover is secured in place to retain the generator in the cage.

To connect the discharge outlet with the liquid in the lowermost part of the reservoir in all positions of the extinguisher, a 50 tube 29 extending longitudinally of the reservoir with its ends adjacent the side and opposite ends of the reservoir is rotatably mounted upon the tube 28 by a coupling 30, and the tube 29 communicates through the 55 coupling with the tube 28 through lateral ports 31 in said latter tube.

To shut off communication between one end of the tube 29 and the discharge outlet when the extinguisher is in an upright 60 position when the generator has been set off to expel the liquid from the reservoir through the lower end of the tube and prevent the gas from being expelled to the atmosphere, a valve 32 is provided to coöperate 65 with a seat connected to or formed at the

end of the tube 29, and when the extinguisher is in inverted position a valve 33 coöperates with a seat at the opposite end of the tube 29. These valves are carried at the ends of a rod 34, whereby when one 70 valve is seated it will operate to unseat the other valve.

In operation the charged generator is placed in the cage 17 when the fire extinguishing liquid is supplied to the reservoir 75 and the cover with the intake tube 29 for the discharge outlet is secured in place, the end of the tube 28 extending into the reservoir to a point adjacent the top of the generator and operating to retain the generator in its carrier or cage, the manually operable valve being in open position and the outlet closed by the valve 6. To use the extinguisher it is inverted when the acid 80 will flow from the bottle 15 onto the soda, the generated gas passing between the walls of the receptacles 9 and 14 through the filtering material in the chamber 9 below the receptacle 14, and through the lateral ports 85 in the tube 10 into the reservoir where its force is exerted on the liquid to discharge the same. In this position of the extinguisher the inlet to the intake 29 uppermost is closed by the valve 33 while the valve 32 will be maintained open due to the 90 connection thereof to the rod 34, the liquid passing up through the tube 29 through the coupling 30 through the lateral ports in the tube 28 unseating the valve 6 and out through the outlet extension 7. It will be 95 obvious that should the extinguisher be placed in an upright position that the liquid will be forced through the end of the intake tube 29 opposite to that through 100 which it flows when the extinguisher is in an inverted position. Furthermore, no matter in what position the extinguisher may be placed horizontally the intake tube 29 will at all times assume a position in the 105 lowermost part of the liquid. Should the extinguisher be set in operation and it is desired not to expel all of the liquid the manually operable valve 8 is closed and by 110 slightly rotating or unscrewing the cover a port 35 in said cover will connect the interior of the reservoir to the atmosphere and permit of the escape of the generated gas through said port.

By the provision of the tube 10 in the generator and as the charge generator, which is in the nature of a cartridge, is placed in its carrier in the reservoir the air in said tube will prevent any of the fire extinguishing liquid entering the generator through 115 said outlet and thereby providing an extinguisher in which the generator is hermetically sealed by the fire extinguishing liquid and prevent any deterioration of the gas generating materials. To prevent endwise 120

125

130

135

movement of the tube supporting coupling 30 on the tube 28 the latter is provided with abutments or collars 36 at opposite ends of the coupling, and the coupling has a counterbore in opposite ends for the engagement of a felt washer 37 to seal the coupling on the tube 28.

Having thus described my invention I claim:

- 10 1. In a fire extinguisher, the combination of a reservoir open at the top and having a removable cover therefor with a discharge outlet for the reservoir; a gas generator; a cage in the bottom of the reservoir in which the generator is removably carried to maintain the generator centrally of the reservoir; and an abutment carried by the cover to engage with the generator to maintain it in the cage, substantially as and for the purpose specified.
- 15 2. In a fire extinguisher, the combination of a reservoir open at the top and having a removable cover therefor with a discharge outlet for the reservoir; a gas generator; a cage in the bottom of the reservoir in which the generator is removably carried to maintain the generator centrally of the reservoir; and means connected to the outlet in the cover adapted to automatically position an inlet to the outlet in the portion of the reservoir which is lowermost and arranged to retain the generator in the carrier.
- 20 3. In a fire extinguisher, the combination of a reservoir having an opening in the top; a removable cover for said opening having a discharge outlet therein for the reservoir; a cage secured centrally to the bottom; a gas generator adapted to be carried within said cage, having an outlet leading into the reservoir; a tube connected to the discharge outlet of the cover to extend into the reservoir with its end closed and adapted to abut against the generator to maintain the generator in the cage, the bore of said tube constituting a continuation of the discharge outlet and having lateral ports; and means to connect said tube with the liquid in the lowermost part of the reservoir in all positions of the extinguisher, substantially as and for the purpose specified.
- 25 4. In a fire extinguisher, the combination of a reservoir having an opening in the top; a removable cover for said opening having a discharge outlet therein for the reservoir; a cage secured centrally to the bottom; a gas generator adapted to be carried within said cage, having an outlet leading into the reservoir; a tube connected to the discharge outlet of the cover to extend into the reservoir, with its end closed and adapted to abut against the generator to maintain the generator in the cage, the bore of said tube constituting a continuation of the discharge outlet and having lateral ports; and a valved inlet to said tube adapted to automatically position itself near the end and side of the reservoir which is lowermost and clear the generator in all positions thereof.

5. In a fire extinguisher, the combination of a reservoir having an opening in the top; a removable cover for said opening having a discharge outlet therein for the reservoir; a cage secured centrally to the bottom; a gas generator adapted to be carried within said cage, having an outlet leading into the reservoir; said generator having means to normally maintain gas generating materials in a separated condition when in an upright position and permitting said materials to mix when the generator is in an inverted position; a tube connected to the discharge outlet in the cover to extend into the reservoir with its inner end closed and abutting against the generator to maintain the generator in the cage when the generator is inverted; an inlet valve mechanism connected to said tube adapted to automatically position an inlet in the lower portion of the reservoir with said inlet open in any position of the reservoir and providing a continuous and unobstructed passage from said inlet to the outlet tube.

6. In a fire extinguisher the combination of a reservoir to contain a fire extinguishing liquid and having an outlet; and a generator to be placed in the liquid in the reservoir having an outlet and means to carry gas generating materials in a separated condition therein in the normal position thereof, and said generator having means to seal the outlet when the generator is placed in the reservoir by the liquid in the reservoir, substantially as and for the purpose specified.

7. In a fire extinguisher, a reservoir to contain carbon tetrachlorid and normally not under pressure; a discharge outlet for said reservoir; and a receptacle to be immersed in the carbon tetrachlorid in said reservoir having an outlet open to the carbon tetrachlorid and arranged to carry bicarbonate of soda and an acid in a separated condition and open to each other in the upright and normal inoperative position of the extinguisher, and said soda and acid adapted to mix when the extinguisher is inverted,

80 the generated gas passing through the receptacle outlet into the reservoir to place the carbon tetrachlorid under fluid pressure to expel the carbon tetrachlorid from the reservoir.

85 8. In a fire extinguisher, the combination of a reservoir having an opening in the top; a removable cover for said opening having a discharge outlet therein for the reservoir; a cage secured centrally to the bottom; a gas generator adapted to be carried within said cage, having an outlet leading into the reservoir; a tube connected to the discharge outlet of the cover to extend into the reservoir, with its end closed and adapted to abut against the generator to maintain the generator in the cage, the bore of said tube constituting a continuation of the discharge outlet and having lateral ports; and a valved inlet to said tube adapted to automatically position itself near the end and side of the reservoir which is lowermost and clear the generator in all positions thereof.

90 9. In a fire extinguisher, the combination of a reservoir having an opening in the top; a removable cover for said opening having a discharge outlet therein for the reservoir; a cage secured centrally to the bottom; a gas generator adapted to be carried within said cage, having an outlet leading into the reservoir; a tube connected to the discharge outlet of the cover to extend into the reservoir, with its end closed and abutting against the generator to maintain the generator in the cage when the generator is inverted; an inlet valve mechanism connected to said tube adapted to automatically position an inlet in the lower portion of the reservoir with said inlet open in any position of the reservoir and providing a continuous and unobstructed passage from said inlet to the outlet tube.

95 10. In a fire extinguisher the combination of a reservoir to contain a fire extinguishing liquid and having an outlet; and a generator to be placed in the liquid in the reservoir having an outlet and means to carry gas generating materials in a separated condition therein in the normal position thereof, and said generator having means to seal the outlet when the generator is placed in the reservoir by the liquid in the reservoir, substantially as and for the purpose specified.

100 11. In a fire extinguisher, a reservoir to contain carbon tetrachlorid and normally not under pressure; a discharge outlet for said reservoir; and a receptacle to be immersed in the carbon tetrachlorid in said reservoir having an outlet open to the carbon tetrachlorid and arranged to carry bicarbonate of soda and an acid in a separated condition and open to each other in the upright and normal inoperative position of the extinguisher, and said soda and acid adapted to mix when the extinguisher is inverted,

105 the generated gas passing through the receptacle outlet into the reservoir to place the carbon tetrachlorid under fluid pressure to expel the carbon tetrachlorid from the reservoir.

110 12. In a fire extinguisher, the combination of a reservoir having an opening in the top; a removable cover for said opening having a discharge outlet therein for the reservoir; a cage secured centrally to the bottom; a gas generator adapted to be carried within said cage, having an outlet leading into the reservoir; a tube connected to the discharge outlet of the cover to extend into the reservoir, with its end closed and adapted to abut against the generator to maintain the generator in the cage, the bore of said tube constituting a continuation of the discharge outlet and having lateral ports; and a valved inlet to said tube adapted to automatically position itself near the end and side of the reservoir which is lowermost and clear the generator in all positions thereof.

115 13. In a fire extinguisher, the combination of a reservoir having an opening in the top; a removable cover for said opening having a discharge outlet therein for the reservoir; a cage secured centrally to the bottom; a gas generator adapted to be carried within said cage, having an outlet leading into the reservoir; a tube connected to the discharge outlet of the cover to extend into the reservoir, with its end closed and abutting against the generator to maintain the generator in the cage when the generator is inverted; an inlet valve mechanism connected to said tube adapted to automatically position an inlet in the lower portion of the reservoir with said inlet open in any position of the reservoir and providing a continuous and unobstructed passage from said inlet to the outlet tube.

120 14. In a fire extinguisher, the combination of a reservoir having an opening in the top; a removable cover for said opening having a discharge outlet therein for the reservoir; a cage secured centrally to the bottom; a gas generator adapted to be carried within said cage, having an outlet leading into the reservoir; a tube connected to the discharge outlet of the cover to extend into the reservoir, with its end closed and adapted to abut against the generator to maintain the generator in the cage, the bore of said tube constituting a continuation of the discharge outlet and having lateral ports; and a valved inlet to said tube adapted to automatically position itself near the end and side of the reservoir which is lowermost and clear the generator in all positions thereof.

Signed at New York city, in the county of New York, and State of New York November, 1916.

GEO. T. PEARSONS.
